UNITED STATES PATENT OFFICE.

ALBRECHT GRAEF, OF NEW YORK, N. Y.

DESIGN FOR A RAZOR-BLADE.

SPECIFICATION forming part of Design No. 29,700, dated November 22, 1898.

Application filed October 19, 1898. Serial No. 694,038. Term of patent 7 years.

To all whom it may concern:

Be it known that I, ALBRECHT GRAEF, a citizen of the United States, residing at New York, in the borough of Manhattan, State of New York, have invented and produced a new and original Design for Razor-Blades, of which the following is a specification, reference being had to the accompanying drawing, which represents the same in side elevation.

10 The leading feature of my design is a razor-blade having a number of medallions of naval heroes at regular intervals thereon.

15 A indicates a razor-blade bearing three medallions *b c d*, representing different naval heroes and arranged so as to provide spaces

for suitable inscriptions or names. Gathered around these medallions are sprigs or twigs of leaves D.

Having thus described my invention, I claim as new and desire to secure by Letters Patent—

The design for a razor-blade, as herein shown and described.

In testimony that I claim the foregoing as my invention I have signed my name in presence of two subscribing witnesses.

ALBRECHT GRAEF.

Witnesses:

PAUL GOEPEL,
M. HENRY WURTZEL.
